Sally S.

UNITED STATES PATENT OFFICE.

KARL S. BRECKENRIDGE, OF CHICAGO, ILLINOIS, ASSIGNOR TO AMERICAN CAN COMPANY, OF NEW YORK, N. Y., A CORPORATION OF NEW JERSEY.

CAN.

Application filed April 16, 1925. Serial No. 23,474.

5 My invention relates to cans of that type adapted to be opened by removal of an encircling tearing strip and to be temporarily closed, after being first opened and during the time the contents are being consumed, by replacement of the upper severed part of the can as a reclosure member.

Cans of this general type have been extensively used in recent years and are highly desirable for many types of products. The usual construction involves the use of a separate interior collar protruding above the tearing strip and providing a friction wall upon which the reclosure may be 15 removably positioned. The cost of this additional member and the operations required for securing it in the can necessarily add considerably to the expense of manufacture. It is, therefore, the principal object of my invention to provide a collarless tearing strip can which can be manufactured at materially less cost than the ordinary interior collar can and which will have most of the advantages of the latter, as well as certain others inherent in its own construction.

20 A highly desirable feature of the invention is that it may be embodied in the ordinary "sanitary", or "packers" type can by a simple and well-known manufacturing operation and thus may be produced with standard machinery. This is important, both from the standpoint of cost and of the character of the resulting container, which may be packed, shipped and handled in the same manner as standard cans of the kind indicated.

25 Other objects and advantages of the invention will be apparent as it is better understood from the following description, which, taken in connection with the accompanying drawings, discloses a preferred embodiment thereof.

Referring to the drawings,

30 Figure 1 is an elevational view of a can in which my invention is embodied; and

Fig. 2 is a view, partly in elevation and partly in section, of the upper part of said can, showing the tearing strip removed and the severed part of the can positioned as a temporary reclosure.

35 In said drawings, illustrating the best manner in which I have thus far contemplated applying the principles of my invention, the reference character 11 indicates the body of the can, which, as stated

above, may be of the ordinary "sanitary" or "packers" type, the ends 12 and 13 being applied in the usual manner. The edges of the body blank are joined in the usual side seam 14 and an encircling tearing strip 15 is formed in the body by means of parallel score lines 16 and 17, which are cut into the blank before the can body is formed. A tongue 18 is provided at one end of the tearing strip and the latter is scored diagonally, as indicated at 19, in what is known as a herringbone score, the purpose of these score lines being to insure against tearing through the strip before it is completely removed.

40 A bead 21 is formed at a distance beneath the tearing strip and the can is necked-in above said bead, as shown at 22, the necking-in operation being well known in the can making industry and being adapted to be performed upon can bodies of the usual and standard form after they have been made up. The operation is inexpensive and cans of the type contemplated by the invention can be produced thereby when they are desired from a stock of standard can bodies 45 which may be on hand. The body diameter, both at the top and bottom, is the same as that of the ordinary "sanitary" can of corresponding size and may be packed in similar cases and stacked in the same way. Furthermore, end members of standard size may be used and the body flanges may be of usual form and are not affected by the necking-in operation. The upper bend 23 of this necked-in part is between the score 50 lines 16 and 17, so that the wall diameter above the tearing strip is greater than the wall diameter beneath said strip. The severed part of the can may, therefore, be replaced as a temporary friction closure, engaging the reduced wall part, there being no necessity for the separate interior collar above referred to.

55 It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

A reclosure cylindrical tearing strip can 60

having in combination a body the top and bottom of which are of equal diameter, a top and bottom united with said body, said body being necked in at a distance below the 5 top so as to be formed with a part of smaller diameter than the upper part of the body and also of smaller diameter than the lower part of the body, and a tearing strip set off around said body, the upper line of said 10 tearing strip being formed on the upper

part of the body which is of larger diameter, and the lower line of said tearing strip being formed on the necked in portion of the body, whereby, after the tearing strip has been removed, the part of the body above the 15 tearing strip will fit outside of and around said necked in portion, and the upper part of the can will be in line with the bottom part of the can.

KARL S. BRECKENRIDGE.
